UNITED STATES PATENT OFFICE.

CHARLES M. ABERCROMBIE, OF BRIDGEPORT, CONNECTICUT, ASSIGNOR TO THE SINGER MANUFACTURING COMPANY, A CORPORATION OF NEW JERSEY.

OVEREDGE SEWING AND CUTTING MACHINE.

1,025,441.

Specification of Letters Patent.

Patented May 7, 1912.

Application filed May 3, 1910. Serial No. 559,050.

To all whom it may concern:

Be it known that I, CHARLES M. ABERCROMBIE, a citizen of the United States, residing at Bridgeport, in the county of Fairfield and State of Connecticut, have invented certain new and useful Improvements in Overedge Sewing and Cutting Machines, of which the following is a specification, reference being had therein to the accompanying drawings.

This invention relates to improvements in sewing machines for making the "so called" overedge, spokestitch or hemstitch seam, and has for its object to broaden the application of such machines by rendering them capable of effecting in a single operation productions which have hitherto required multiple operations.

In the manufacture of hand towels it has been the common practice to weave the towels separately or to cut lengths of toweling from the web and hem fold and secure the opposite ends thereof by lines of hemstitching; but in connection with recent productions it has been found desirable to hemstitch the raw edges, thereby obtaining a more desirable finish and effecting a substantial saving in material for a given size of towel; and, so far as applicant knows, such overcast or hemstitch finish has been produced by first forming the individual towels and afterward overcasting the edges, usually by using a hemstitch sewing machine. The purpose of the present invention is to form two lines of overedge stitching simultaneously and at the same time sever the fabric intermediate said lines of stitching, thereby materially reducing the cost of production and effecting a more uniform finish.

The invention is herein shown in connection with the commercial hemstitch sewing machine represented by U. S. patent to J. Walker, No. 634,970, dated Oct. 17, 1899, but as the practical operation of the invention is not dependent upon any specific form of construction for giving to the needles and the piercer the necessary movements for producing slightly separated parallel rows of overedge stitching, only so much of the machine proper has been illustrated as is deemed essential for an understanding of the invention.

Referring to the accompanying drawings illustrating the invention, in the several

figures of which like parts are similarly designated, Figure 1 is a view in front end elevation of a portion of the sewing machine bed-plate and bracket arm illustrated in the previously referred to patent, together with the piercer, one of the needles, the cloth-pressers and the cloth-presser-carrying bar, the cutting mechanism being shown in front side elevation mounted upon the cloth presser-carrying bar. Fig. 2 is a front end elevation, in perspective, of Fig. 1. Fig. 3 is a rear side elevation, in perspective, of Fig. 1. Fig. 4 is a perspective view of the cutting mechanism detached from the cloth-presser-carrying bar. Fig. 5 is a perspective view of the throat-plate. Fig. 6 is a perspective view of one form of production effected by the improved mechanism.

1 represents the bed-plate of the sewing machine, 2 the bracket arm, 3 the front and 4 the back slide plate, 5 the throat-plate, 6 the feed-dog, 7 and 8 the needles, 9 the needle-actuating bar, and 10 the piercer carried by the bracket 11 which is secured by screw 12 upon the piercer-carrying bar 13.

14 and 15 represent the cloth-presser brackets, the latter of which is secured by screw 16 to the cloth-presser-carrying bar 17. The bracket 14 is mounted to move vertically upon the bar 17 and is held depressed by the spring 18 in a manner common to machines of the class herein referred to.

19 and 20 represent the commonly-employed rocking pressers.

To the lower end of the needle-actuating bar 9 is secured, by a clamp 21 and screws 22, 23, the needle-bar bracket 23 to which are pivotally secured, by screws 24 and 25, the needle brackets 26 and 27. The bracket 26 carrying the needle 7 and the bracket 27 carrying the needle 8 are operatively connected, through the rods 28 and 29, respectively, with the actuating mechanism of the sewing machine to cause each needle to be moved sideways to pierce the fabric in different vertical planes, causing each needle thread to be concatenated with its coacting under thread to form separate rows of stitches which are interlocked to form binding stitches as in the device of Patent No. 634,970 previously referred to; and as in the device of said patent, when the needles descend with the piercer to form the inner or edge stitches, said needles enter the opening formed by said piercer, thus effecting

the openwork or spokestitch seam. Secured to the lower end of the needle-actuating bar by a screw 30 is a thread-guiding wire 31 which is provided for holding the upper threads in proper alinement with the needles.

5 The cutting mechanism comprises a main bracket 32 provided at its lower end with a stationary shear blade 33, whose cutting edge is parallel with the feed of the fabric 10 and in line with and at the rear of the piercer, the upper end of said bracket, in the present instance, having formed integrally with it an arm 34 constituting a pinch bracket for suspending the cutting mechanism upon the lower end of the cloth-presser carrying bar 17, a screw 35 serving to secure said arm upon said bar.

20 36 represents a cutter-actuating lever pivoted upon the stud bolt 37, said bolt being secured by screw 38 in the bracket 32. The rocking shear blade 39 is also pivoted upon said bolt and is secured to move with the cutter-actuating lever 36 by the lug 40 entering the notch 41 formed in the blade 39.

25 42 represents a spring, one end of which is attached, by screw 43, to the cutter-actuating lever 36, its opposite end being attached to the free end of the bracket 44 which is secured by screw 45 to the main bracket 32, said spring acting to resiliently hold the lever 36 in opposition to the downward movement of the needle-bar bracket 23 carried by the needle-actuating bar 9, said bracket acting upon the curved portion 46 30 of said actuating lever to rock the blade 39 into cutting relationship with its coacting blade 23.

40 47 represents a rib or incline formed on the upper surface of the throat-plate for leading the material over the cutting edge of the blade 33.

45 The throat-plate 5 is provided with the usual feed-dog openings, 48, 48, and needle and piercer opening 49, and is secured to the bed-plate 1 by screw 51.

50 In the operation of the device when employed in connection with the stitch-forming and cloth-feeding mechanism represented by Patent No. 634,970, the needles are given lateral or swinging movements back from the cutting line, as when forming the depth stitch 52, a distance sufficient to insure that the clusters 53 of the threads forming the fabric 54 will be held bound together substantially as shown in Fig. 6.

Claims:—

1. In a sewing machine, a stitch-forming mechanism including two needles each having sidewise movements to form parallel lines of stitches, a piercer having vertical movements to form openings in the fabric being acted on into which said needles descend in the formation of the inner lines of said stitches, and a cutting mechanism 60 65 whose coacting blades are arranged in a line

corresponding to the direction of the feed of said fabric and operatively connected with the actuating mechanism of the sewing machine to sever said fabric at the rear of and in line with said piercer openings during the stitching operation.

2. In a sewing machine, a stitch-forming mechanism including two needles each having sidewise movements to form parallel lines of stitches, a piercer having vertical movements to form openings in the fabric being acted on into which said needles descend in the formation of the inner lines of said stitches, a cloth presser mechanism including a vertically moving cloth-presser carrying bar, and a cutting mechanism secured to the lower end of said bar whose coacting blades are arranged in a line corresponding to the direction of the feed of said fabric and operatively connected with the actuating mechanism of the sewing machine to sever said fabric at the rear of said piercer and in line with said piercer openings during the stitching operation.

3. In a sewing machine, a stitch-forming mechanism including two needles each having sidewise movements to form parallel lines of stitches, a piercer having vertical movements to form openings in the fabric being acted on into which said needles descend in the formation of the inner lines of said stitches, a cutting mechanism whose coacting blades are arranged in a line corresponding to the direction of the feed of said fabric and operatively connected with the actuating mechanism of the sewing machine to sever said fabric at the rear of and in line with said piercer openings, and a throat-plate provided with a rib over which said fabric is advanced to said cutting mechanism.

4. In a sewing machine, a stitch-forming mechanism including a needle-bar carrying two eye-pointed needles each of which are given sidewise movements to form parallel lines of stitches, a piercer having vertical movements to form openings in the fabric being acted on into which said needles descend in the formation of the inner lines of said stitches, a cutting mechanism whose coacting blades are arranged in a line corresponding to the direction of the feed of said fabric and operatively connected with said needle-bar to sever said fabric at the rear of said piercer and in line with said piercer openings, and a throat-plate provided with a rib over which said fabric is advanced to the action of said cutting mechanism.

5. In a sewing machine, a stitch-forming mechanism including a needle-bar carrying two eye-pointed needles each of which are given sidewise movements to form parallel lines of stitches, a piercer having vertical movements to form openings in the fabric

being acted on into which said needles descend in the formation of the inner lines of said stitches, a cloth-presser mechanism including a vertically moving cloth-presser carrying bar, a cutting mechanism secured to the lower end of said bar whose cutting blades are arranged in a line corresponding to the direction of the feed of said fabric and operatively connected with said needle-bar to sever said fabric at the rear of said

piercer, and a throat-plate provided with a rib over which said fabric is advanced to the action of said cutter.

In testimony whereof, I have signed my name to this specification, in the presence of 15 two subscribing witnesses.

CHARLES M. ABERCROMBIE.
